COMBINATION INHALER, CIGARETTE FILTER, AND HOLDER

Siegfried Furstenberg, New York, N. Y.

Application August 25, 1941, Serial No. 408,201

1 Claim. (Cl. 128—200)

The present invention relates generally to the field of inhalers and smokers' articles, and more particularly to combination inhaler, cigarette filter and holder.

Among the principal objects of the invention lies the provision of structure of the class described wherein the same may be altered or adjusted so that it may have a varied use.

Another object of the invention lies in the provision of structure whereby an inhaler is provided capable of use with various volatile materials of a medicinal or other nature, and which does not obviously betray to others the fact that the user is not actually smoking a cigarette.

Another object herein lies in the provision of structure by suitable adjustment of which the same may be adapted for use with a cigarette actually burning so that the smoke from the cigarette becomes mixed with volatile materials as described above.

Another object herein lies in the provision of a combination inhaler, cigarette filter and holder, wherein by suitable adjustment the inhaling and filtering features may be omitted and the device used solely for the purpose of holding the cigarette in the mouth or lips of the user.

Another object herein lies in the provision of a device of the character described, which is readily taken apart for the replacement of the volatile materials, for adaptation of different uses and for cleaning or repair.

A feature of the invention lies in the fact that the same is capable of large scale production at low cost so that the same may have a consequent wide sale and use.

By reason of the simplicity and novel arrangement of the parts, the same is readily adjusted by anyone having no special skill and is foolproof in operation.

It is a well known fact that many individuals who smoke a great deal or to excess would like to give up the habit or at least reduce the number of cigarettes smoked during the day. Besides whatever stimulating effect the nicotine may have upon a smoker, there is also the psychological effect of carrying a lighted cigarette in the hands or lips which gives the user a certain relaxation of tension.

In accordance with the present invention, the smoker is able to hold what appears to be a lighted cigarette in his hand or mouth, thus creating the impression to others that he is actually smoking, as well as giving him a certain psychological relaxation of nervous tension. The volatile materials in the device are inhaled and have

both a beneficial effect upon the previously irritated nasal, throat and bronchial passages, and produce a pleasant and satisfying taste in the mouth. Even where the device is used for the purpose of reducing the total number of cigarettes smoked during the day, the alternation of the use of this device between the cigarette smokings improves the condition of the smoke carrying passages of the user and also reduces the taste fatigue which occurs from constant smoking.

As will be further described below, when desired, the same device may be adjusted for use as a cigarette holder and filter, or a cigarette holder alone.

These objects and other incidental ends and advantages will more fully appear in the progress of this disclosure and be pointed out in the appended claim.

20 In the drawing forming a material part hereof, similar reference characters designate corresponding parts throughout the several views of each embodiment.

Figure 1 is an elevational view of a first embodiment of the invention shown in actual size.

Figure 2 is an enlarged vertical longitudinal sectional view of Figure 1.

Figure 3 is a vertical transverse sectional view as might be seen from the plane 3—3 on Figure 2.

30 Figure 4 is an enlarged central longitudinal sectional view of a second embodiment of the invention.

Figure 5 is a view taken similarly to Figure 4 showing an adjusted form of the second embodiment of the invention as adapted for use as a cigarette holder.

Figure 6 is an elevational view, taken similarly to Figure 1, actual size, of the second embodiment of the invention as adjusted for use as a cigarette holder and filter.

40 Figure 7 is a fragmentary enlarged vertical longitudinal sectional view of the forward portion (the left hand end) of Figure 6.

Turning now to the first embodiment of the invention illustrated in Figures 1 to 3, inclusive, the combination inhaler, cigarette filter and holding device is generally indicated by numeral 10. Broadly speaking, the device 10 comprises a casing or main cylinder 11, a volatile material carrying chamber and filter tube 12, and a mouthpiece, bit or holder 13.

The main cylinder 11 is preferably a true cylinder in shape, having a reduced portion 14 connected to the main cylinder 11 by the shoulder 15. The main cylinder 11 and the reduced

portion 14 form a continuous tube, the forward end being closed by a plug 17. The cylinder 11 is preferably composed of fused ceramic material, such as porcelain, although other vitreous materials may be used. The advantage of the use of porcelain lies in the fact that the same, when composed of a white clay, forms a close resemblance to an ordinary cigarette in the outer appearance thereof. The cylinder may, however, be made of other materials, such as thermoplastic artificial resins, such as "Bakelite," ureaplastic compounds or methyl methacrylate compounds. Since the outer wall surface of the cylinder 11 rearwardly of the shoulder 15 is white and gives the appearance of a cigarette, the forward reduced portion 14, together with a part of the annular shoulder 15 as well as the forward exposed surface of the plug 17, is treated to give the appearance of an ash-covered burning cigarette end. This is accomplished by first coating the said shoulder, reduced portion and plug end with the layer 18 of "copper bronze," the "copper bronze" being a mixture of fine metallic copper particles in a suitable transparent binder such as cellulose acetate dissolved in amyl acetate. Sufficient plasticizers, or other materials to retard the drying of the said binder are introduced therein so that the same has an adhesive character, and before the same is fully dry, ash resembling particles 19 are dusted on. These particles adhere and give the impression of a glowing cigarette end covered with cigarette ashes. The ash-resembling particles 19 are preferably formed from a mixture of small white, gray and black particles made by coloring sand grains with different colored pigments or by using granular material having the desired colored characteristics, such as white sand, grey sand and granulated coal or similar black material.

The rear end 21 of the cylinder 11 is provided with an internal thread 22 which is adapted to threadedly engage an external thread 23 on the shank 24 of the bit 13. The cylinder 11 at the forward end 16 thereof adjoining the shoulder 15 is provided with an air inlet orifice 25. The orifice 25 is of relatively small diameter, being large enough only to admit sufficient air for the proper use of the device 10, and its location among the ash-resembling particles 19 permits its concealment.

The bit 13 may be of any desired external configuration, but preferably takes the form shown, which is intended to present the external appearance of a stereotyped form of cigarette holder. The bit 13 is provided with an internal bore 27 which extends from the rear end 28 of the bit 13 forwardly through the shank 24, but has the diameter thereof enlarged within the shank 24 to form the shank bore 29. Between the body 30 of the bit 13 and the shank 24, there is an annular shoulder 31 presenting a front face 32. The rear end of the cylinder 11 is adapted to abut against the face 32 when the cylinder 11 is screwed into its fully seated position. The bit 13 may be composed of any suitable material, as for example, "Bakelite," amber, hard rubber, or similar material.

The volatile material carrying chamber and filter tube 12 is preferably composed of glass, is cylindrical in shape, and the body portion thereof 33 has an external diameter preferably slightly less than the internal diameter of the cylinder 11 so that the same may be freely inserted therein or removed therefrom. The length of the tube 12 is such that the forward end 34 thereof is

adapted to be disposed a sufficient distance rearwardly of the inner end of the plug 17 so that air may enter through the orifice 25 into the end 34. The rear end of the tube 12 is provided with a neck 36 of reduced diameter. The diameter of the neck 36 is preferably slightly less than the internal diameter of the shank bore 29 and a rubber spacer or gasket 37 serves to frictionally and replaceably position the tube 12 with relation to the bit 13. The resiliency afforded by the gasket 37 permits slight movement of the tube 12 with relation to the shank 24 without breakage of the tube 12 when the same is composed of brittle material. Where desired, the tube 12 may be composed of a suitable thermoplastic material, such as "Lucite." As seen in Figure 2, the volatile material 40 is disposed within the tube 12 and may be maintained in position therein by any suitable porous plug 41, such as absorbent cotton.

20 The use of the device is a relatively simple matter. Any desired volatile material 40 may be placed within the tube 12 when the cylinder 11 has been unscrewed and the plug 41 removed. The replacing of these parts to the positions shown 25 in Figure 2 renders the device operative, and sucking on the end 28 by the smoker will draw air through the orifice 25, the tube 12, the neck 36 and the bore 27. As the volatile material becomes consumed, it may be replaced.

30 Turning now to the second embodiment of the invention illustrated in Figures 4 to 7 inclusive, the device, generally indicated by numeral 10', differs principally from the first embodiment in the fact that the reduced portion 14' is a plug in 35 and of itself so that the forward end 16' is removable by reason of the fact that the same has a reduced shank 50' which threadedly engages an internal thread on the forward end of the casting or cylinder 11'. The plug 14' may be treated 40 to resemble a burning cigarette end in a manner similar to that described above. The plug 14' contains a channel or orifice or air admitting orifice 25'. The cylinder 11' is otherwise of substantially the same construction as the cylinder 45 11 previously described, and the same, for the purpose of avoiding undue repetition, is marked in the drawing with singly primed characters at those parts corresponding to the first embodiment.

50 The tube 12' may be substantially identical with the construction of the tube 12 previously described, and here again, for the purpose of avoiding needless repetition, the parts are given corresponding singly primed reference characters.

55 The bit 13' differs principally from the first embodiment in that the bore 27' is expanded in a conical shape to form the conical bore 51' while the shoulder 31' has an internal thread adapted to receive the union 52'. The union 52' includes 60 an enlarged bit engaging portion 53' and a reduced main cylinder engaging portion or shank 24'. The shank 24' has an external thread and is adapted to be screwed into the rear end 21' of the cylinder 11'. The union or shank bore 29' 65 is adapted to receive the gasket 37', including the neck 36'.

When the second embodiment is used in a manner similar to the first embodiment, for the purpose of replacing the volatile material 40', 70 it becomes necessary to unscrew only the rear end 21' of the cylinder 11' from the threaded shank 24'.

When it is desired to use the bit 13' only as a cigarette holder, the union 52' is removed by 75 separating the enlarged bit engaging portion 53'

by unscrewing the same from the shoulder 31'. A cigarette 60' may then be inserted into the holder or bit 13' in a manner shown in Figure 5 and the threads 55' help to hold the cigarette 60' in place. The diameter of the space between opposite portions of the threads 55' is substantially equal to or slightly less than the normal diameter of cigarettes sold in trade. If for some reason the diameter of the cigarette 60' should be less than the normal diameter, forcing the same rearwardly against the converging inner walls of the conical bores 51' will suitably position the rear end 61' of the cigarette thereagainst and frictionally engage the same thereat.

Where it is desired to use the device shown in Figure 4 as a cigarette filter, it becomes necessary only to remove the plug 14' and to insert in its stead the cigarette 70'. This is shown in Figures 6 and 7. When so adjusted, air enters the forward end 12' of the cigarette 70', and, forming smoke with the burning tobacco, passes through the cigarette 70', thence through the tube 12' and the neck 36', the bore 29', the bore 51', and the bore 27'. The smoke thus becomes filtered and flavored. The rear end 71' of the cigarette 70' is readily detachably engageable by slightly compressing the same within the internal threads at the forward end of the cylinder 11'.

It may thus be seen that the second embodiment of the invention may have the three different functions previously described, conveniently available.

In conclusion then, there has been disclosed

novel combination inhaler, cigarette filter and holding devices which are simple and foolproof in construction and operation, are sanitary in use and may be made in relatively large quantities at low cost.

I wish it to be understood that I do not desire to be limited to the exact details of construction shown and described, for obvious modifications will occur to a person skilled in the art.

I claim:

A combination inhaler, cigarette filter and holder for alternative use with a cigarette, comprising: a main cylinder of an outer diameter and appearance similar to said cigarette, and having a detachable plug covered with imitation ashes, said plug being inserted in and threadedly engaging the forward end of said main cylinder, said plug having an air admitting orifice; a transparent volatile material carrying tube disposed within said cylinder and concealed thereby; said tube having a reduced rear neck with a resilient gasket thereon; volatile material within said carrying tube; a union having an enlarged bit engaging portion, a reduced main cylinder engaging portion, and a central bore; a mouthpiece bit having a second bore and adapted to detachably engage the said bit engaging portion of the union; said cylinder being detachably engageable at the rear end thereof upon the outer surface of the reduced main cylinder engaging portion of the union; the gasket on the rear end of said tube being detachably engageable within the bore in the union.

SIEGFRIED FURSTENBERG.
